(57) **CLAIM**

The ornamental design for solar charging device, as shown and described.

DESCRIPTION

FIG. 1 is a front view showing my new solar charging device design;

FIG. 2 is a top view thereof;

FIG. 3 is a left-side view thereof, the right-side view being a mirror image thereof;

FIG. 4 is a rear view thereof; and,

FIG. 5 is a left-side and front perspective view thereof.

The portions of the design shown in broken lines form no part of the claimed design.
